UNITED STATES PATENT OFFICE.

JULIUS H. BACH, OF CHICAGO, ILLINOIS.

PROCESS OF BURNING BRICK.

1,008,300.

Specification of Letters Patent. Patented Nov. 14, 1911.

Application filed January 13, 1911. Serial No. 602,484.

To all whom it may concern:

Be it known that I, JULIUS H. BACH, a citizen of the United States, residing at Chicago, in the county of Cook and State of Illinois, have invented certain new and useful Improvements in Processes of Burning Brick, of which the following is a description, reference being had to the accompanying drawings, forming a part of this specification, in which corresponding letters of reference in the different figures indicate like parts.

The object of my invention is to provide a continuous process adapted to the burning of bricks made from a highly porous clay. Heretofore it has been customary to burn bricks of this character in a single "clamp" or kiln and to allow the aqueous vapor or "water-smoke" to pass upwardly into the atmosphere. So far as I am aware, all attempts to burn bricks of this character by what is commonly known as the "continuous process", which, generally stated, consists in successively passing the heat and vapors from one section of a kiln to another and cooling the previously burned sections by the indrawn air, while successful with the denser clays common to Ohio and the Atlantic States, have failed completely when applied to the more porous clays such, for example, as are found in Chicago and vicinity. In burning the denser clays it has been found essential to use slow and comparatively light fires at the start in order to drive off all aqueous vapors as rapidly as possible in advance of the more intense heat, so as to prevent the bricks from cracking and becoming otherwise distorted and misshapen. Under this method about two weeks is required to burn a kiln of bricks of the character last mentioned. In burning porous bricks however, I have discovered that they should be subjected to a quick and intensely hot fire from the beginning in order, among other things, to utilize the vegetable and other carbonaceous matter in the brick, which, if allowed to be consumed in a slow fire, will be lost and its heat dissipated to no purpose. Any attempt thereafter to heat the brick to the required temperature necessitates an excessive and wasteful expenditure of fuel and results in an inferior and unsatisfactory product. I am enabled to overcome the difficulties stated and to accomplish the object of my invention in the manner hereinafter more par-

ticularly described and definitely pointed out in the claims.

In the drawings, Figure 1, is a side elevation of a brick kiln adapted to carry out my improved process. Fig. 2, is an enlarged transverse sectional view thereof taken upon the line 2—2, Fig. 1. Fig. 3, is an enlarged plan view of a portion of said kiln the same being partially broken away to show the top ducts, and Fig. 4, is an enlarged side elevation of portions of said kiln partially broken away to show the interior.

Referring to the drawings, which are intended to illustrate one means for carrying out my improved method, 1 represents generally a brick kiln which consists preferably, of an elongated structure comprising the usual scoving or casing 2, forming the sides and ends and a top or covering 3 of brick and earth. The dried brick 4, to be burned, are somewhat closely stacked within the kiln substantially as represented in the drawings, so as to form small but uniform spaces between them throughout the mass, thereby preventing an excessive or uneven draft in any one part during the process of burning. The usual transverse fire-chambers 5, Fig. 4, are formed in the brick when stacked, said chambers being located opposite to the usual firing arches 6, formed in the side walls. Pipes 7, connected with a source of oil or gas supply, not shown, enables fuel, preferably oil, to be conducted to any well known form of burners located in the fire chambers, or wood or coal, preferably the former, may be used for heating. The chambers 5 are intended to serve either as air ducts or for firing according to the stage of advancement in the process. A series of transverse draft ducts 8, are formed in the top of the kiln in the same vertical plane with the ducts or fire-chambers 5. Longitudinal ducts 9 are also provided in the top of the kiln in communication with the ducts 8. Openings 10, Fig. 3, are formed in the top in communication with the ducts 9 to permit the escape of water-smoke when necessary. These are intended to be normally closed by any form of damper or cover not shown. The ducts 8, in the outer walls, which are intended to be normally closed by means of plugs or otherwise, are adapted to be connected by means of pipes 11 with vertical ducts 12, Fig. 2, in communication with the chambers 5, and also with transverse conduits 13 leading to a

main conduit or tunnel 14 beneath and extending lengthwise of the kiln and in communication with a fan 15, Fig. 1.

In advance of each of the ducts 8 is placed some kind of a partition or barrier 16, Fig. 4, which may consist of a removable partition of sheet metal or other suitable material but is preferably formed from paper or straw-board and inserted between the tiers of bricks so as to divide the kiln into a predetermined number of sections, and to prevent a back-flow of air from an unburned section to a preceding one which is being fired. Removable hoods 17, of any approved construction, are adapted to cover or shield any arches which may be opposite ducts which are being employed as draft ducts.

In carrying out my improved process, I first fire preferably about two arches in the first section as indicated at the right in Fig. 4, using the natural or "up draft" and allowing the smoke and vapor to escape upwardly into the atmosphere, a small portion at the beginning of the kiln being left open or uncovered for this purpose. When the desired degree of heat is attained, usually from about twenty-two hundred to about twenty-four hundred degrees Fahrenheit, I place the pipes 11 and hoods 17 in position at the forward arch of the first section and apply the fan draft. This causes a suction in the upper and lower ducts 8 and 5 respectively which makes a differential draft greater below than above from the rear of the kiln. In the meantime care should be taken to prevent the vapor or "water smoke" from escaping too rapidly by carefully controlling the dampers 10 at the top. The location and relative advance of the vapor may readily be determined by one skilled in the art by merely inserting a stick or other object into the arches or through sight-holes which may be provided for the purpose. As long as moisture appears upon the stick it is a proof that vapor is present at the point tested. Inasmuch as heat tends to rise and drive off the vapor at the top of the kiln, the drafts and dampers should be so manipulated as to hold the vapor back at the top so that the line of heat advancement will be in an inclined plane downwardly and forwardly substantially as indicated by the dotted lines shown in Fig. 4. In order to accomplish this the ducts 5 should be larger than the ducts 8 so that the greater draft shall be from below. When the line of maximum heat shall have advanced at the bottom to, at or about the last arch in the section, as indicated by the dotted line 18, Fig. 4, the pipes 17 may be removed and the wall openings opposite to the ducts 8 closed with dampers, clay or otherwise. The fan draft is then applied to the second section. If the partition 16 in the second section is made of paper it will

be burned by the approaching heat when the firing may be advanced to the second section. Fires should be successively advanced in the arches of the second section to force the heat to the desired maximum while the water-smoke is held back in the manner indicated to prevent the heat from being too rapidly dissipated. I have found in practice that the inclined water-smoke line should be kept at a distance of from about five to eight feet in advance of that of maximum heat. Should the vapor line tend to advance too rapidly the heat where needed will be lowered and cannot again be recovered. When this tendency is indicated, the drafts should be regulated to hold the vapor back and the heat forced where the maximum degree is desired before the carbonaceous matter is burned from the bricks. The several lines from that indicating vapor back to white heat are indicated in Fig. 4, viz. "black heat" "cherry red," "bright red" and "maximum." If the vapor line is not maintained in substantially the relation indicated, the heat will advance rapidly forwardly and upwardly and having driven off the vapor, the carbonaceous matter in the brick will be consumed without having raised the heat to more than about six hundred degrees. Any attempt to reburn the brick will result in loss of time and effort as well as to produce an inferior if not worthless product.

The kiln indicated is largely diagrammatic and may be varied indefinitely without departing from the method involved which contemplates the use of a sectional kiln having means for successively advancing the heat from section to section and holding back the vapor to enable the heat to be rapidly raised to a maximum degree.

By means of my improved process, I am enabled to burn a kiln of porous brick in about two days.

Having thus described my invention, what I claim and desire to secure by Letters Patent is:—

1. The method, substantially as described, of burning porous bricks in a kiln, which consists in firing the bricks in a given zone in the kiln to a predetermined degree of heat, advancing the heat in the kiln by forced artificial draft from a predetermined advance zone, forcing the firing in the burning zone to insure a maximum degree of heat in the brick by the time the carbonaceous matter therein is entirely consumed, holding the vapor back in advance of the fire to prevent premature dissipation of heat energy and successively advancing the draft and firing zone throughout predetermined sections of the kiln while maintaining the vapor and heat zones in a substantially constant relation to each other.

2. The method, substantially as described,

of burning brick made from porous clay which consists in placing the brick in a kiln with substantially uniform spaces between them throughout the mass, dividing the kiln 5 into separate sections, firing the first section by natural draft until a maximum heat is obtained at the beginning thereof, applying artificial draft at the forward end of the section and holding the water-smoke back 10 to a predetermined distance in advance of the maximum heat and advancing water-smoke and heat successively from section to section.

3. The method, substantially as described, 15 of burning porous brick, which consists in stacking the brick with substantially uniform spaces between them throughout the kiln, dividing the kiln into separate sections of predetermined length, firing the first section to obtain a maximum heat at the beginning thereof, preventing a back draft from the second section, inducing an artificial draft from the top and bottom of the forward end of the section, firing a predetermined number of arches back of said forward end, holding the water-smoke in advance of and partially over the point of maximum heat and successively advancing the water-smoke and maximum heat at an 20 arbitrary distance from each other from section to section.

4. The method substantially as described, 25 of burning porous bricks which consists in stacking the bricks in a kiln, firing the same at a given initial point by natural draft until white heat is obtained, applying a forced draft at a predetermined distance forward of said initially-heated zone, pre-

venting a back draft from that part of the kiln to which said forced draft is applied, 40 holding the vapor back in an upwardly and rearwardly inclined plane in advance of the heat zone to prevent a dissipation of heat at the top of the kiln, firing the kiln successively in advance of the maximum heated 45 zone to rapidly advance said zone and repeating the operation with the firing and forced draft continuously throughout successive predetermined sections of the kiln.

5. The method, substantially as described 50 of burning porous bricks in a kiln, which consists in firing the bricks in a given zone in the kiln to from about twenty-two hundred to about twenty-four hundred degrees Fahrenheit, advancing the heat in the kiln 55 by forced artificial draft from an arbitrarily selected zone in advance of the heat, forcing the firing in the burning zone to insure the desired degree of heat in the bricks by the time the carbonaceous matter therein is consumed, holding the vapor at a distance in advance of the maximum heat of from about five to about eight feet and in a rearwardly and upwardly inclined plane so that a portion of the vapor may be above the fire and 60 successively advancing the draft and firing zones throughout predetermined sections of the kiln.

In testimony whereof, I have signed this specification in the presence of two subscribing witnesses, this 30th day of December 1910.
